DESIGN FOR A TEXTILE FABRIC

Robert H. Coe, Worcester, Mass.

Application April 2, 1942, Serial No. 106,432

Term of patent 3½ years

To all whom it may concern:

Be it known that I, Robert H. Coe, a citizen of the United States of America, residing in Worcester, county of Worcester and State of Massachusetts, have invented a new, original, and ornamental Design for a Textile Fabric, of which the following is a specification, reference being had to the accompanying drawing, forming part thereof, wherein the figure of the drawing is a plan view of a textile fabric showing my new design.

I claim:

The ornamental design for a textile fabric, substantially as shown.

ROBERT H. COE.
